HYDRAULIC POWER LIFT

Elmer McCormick and Merlin Hansen, Waterloo, Iowa, assignors to John Deere Tractor Company, Waterloo, Iowa, a corporation of Iowa

Application April 19, 1937, Serial No. 137,651

9 Claims. (Cl. 137—139)

The present invention relates to hydraulic mechanisms, and more particularly to improvements in hydraulic mechanisms for tractors and the like for use as power lift mechanism therefor.

Hydraulic power lift mechanism of this general type is illustrated and described in the application of Elmer McCormick, Milford D. Stewart, and Wayne H. Worthington, Serial No. 749,706, filed October 24, 1934, now United States Patent No. 2,107,760, issued February 8, 1938, and the present invention relates to modifications and improvements in such mechanism.

The principal object of the present invention is the provision of improved control means for the hydraulic mechanism whereby it is unnecessary for the operator to hold the control lever or foot pedal down for any given length of time during the raising or lowering cycle. In this connection, the present invention contemplates the provision of such control means that once the foot pedal is pressed down sufficiently to start the raising or lowering operation, the pedal may be released and the mechanism will complete its cycle of operation. The pedal may be pressed down as rapidly or as slowly as the operator desires, or it may be held down indefinitely without interfering with the normal operation of the mechanism. In the present construction, also, if the foot pedal is released before it is pressed down sufficiently to start the raising or lowering operation, the entire mechanism will return to the position it occupied before the foot pedal was actuated, and the raising or lowering operation will not be completed.

Another object of the invention is the provision of improved means whereby the operator can quickly adjust the power lift so that the rate of movement of the actuating piston thereof in the lowering operation may be regulated to thereby control the speed of lowering of the implements associated with the power lift mechanism.

A further object of the invention is to provide improved means for automatically returning the power lift rock shaft to a position corresponding to the lowered position of the implements when the power lift is actuated to return to such position, regardless of whether or not any implements are attached to such rock shaft.

A still further object of the invention is the provision of a lateral passage for supplying oil from the reservoir to the bearing compartment for the power take-off shaft bearing which is positioned beneath the reservoir, and to provide a sump at one side of said bearing compartment into which grit and metal particles picked up by

the oil may settle, whereby such foreign matter will be prevented from entering the bearing compartment below the reservoir.

A still further object of the present invention is the provision of an overload release valve so positioned that access may be had to the valve from the outside of the power lift casing, thereby making it unnecessary to remove such casing for that purpose.

10 Other objects and advantageous features of the present invention will be apparent from the following description of the preferred embodiment of our invention taken in connection with the accompanying drawings, in which—

15 Figure 1 is a vertical longitudinal section taken through the rear end of a tractor in which the present invention has been embodied; Figure 1 corresponding to a section taken along the line 1—1 of Figure 2;

20 Figure 2 is a rear view, looking forwardly, of the construction illustrated in Figure 1, with certain parts of the casing members being shown in section in order to better illustrate the operating mechanism;

25 Figure 3 is a vertical section taken along the line 3—3 of Figure 2 showing the controlling valve mechanism in the position corresponding to the lowered position of the apparatus;

30 Figure 4 is a section similar to that illustrated in Figure 3, and showing the controlling valve mechanism in the position to which it is moved in the raising operation;

35 Figure 5 is a section similar to that illustrated in Figures 3 and 4, and showing the controlling valve mechanism in the position corresponding to the hydraulically locked raised position of the apparatus;

40 Figure 6 is a fragmentary horizontal section taken along the lines 6—6 of Figures 1 and 2, and showing the valve means for regulating the return flow of the fluid from the cylinder;

45 Figure 7 is a vertical section taken along the line 7—7 of Figure 2, and showing the stop means for the valve actuating mechanism and the means for releasing said stop means;

50 Figure 8 is a fragmentary vertical section taken along the line 8—8 of Figure 1, and showing the means for automatically returning the rock shaft to lowered position when the power lift has been actuated to return to such position;

55 Figure 9 is a longitudinal section taken along the line 9—9 of Figure 3, and showing the overload release valve between the pressure channel and the reservoir;

Figure 10 is a horizontal section taken along

the line 10-10 of Figure 2, and showing the means for supplying oil to one of the power take-off shaft bearings; and

Figure 11 is a vertical section taken along the line 11-11 of Figure 1, and illustrating the several integral cam elements of the controlling valve mechanism.

Referring now to the drawings, as shown in Figure 1, the reference numeral 1 indicates the rear portion of a combined crank case and supporting framework of a tractor of well known construction, and 2 indicates the rear axle housing of such a tractor, such rear axle housing in the present case being of the banjo type. Such axle housings comprise laterally directed housing extensions (not shown) in each of which a drive shaft 3 is journaled by any suitable means. Each of said drive shafts 3, one of which is shown in Figure 1, carries a large driving gear 4, said gears being actuated by suitable transmission mechanism and differential means which are indicated as an entirety by the reference numeral 5.

While our improved hydraulic power lift has been illustrated in connection with and mounted on a farm tractor in view of the fact that certain features of our invention are more particularly concerned with providing improved power lift apparatus for such tractors, it is to be understood, of course, that in its broader aspects our invention is not to be limited to such association, and may be applied in any other situation to which it is applicable.

In its preferred form our hydraulic power lift mechanism comprises a unit that is adapted to be bolted over the rear opening 6 of the axle housing 2, and includes a central housing 7 that is adapted to be secured, as by bolts 8, over such rear opening 6 in lieu of the usual cover plate that covers such opening in tractors of the above mentioned type. The central housing 7 includes a forward wall 11 provided in its upper portion with an opening 12, and a cylinder 13 is secured over this opening and extends forwardly substantially into the body of the tractor between the driving gears 4 above mentioned. The forward end of the cylinder 13 is closed, and its rear end is flanged as shown at 14 and secured by bolts 15 over the opening 12 in the central housing 7. Slidably mounted within the cylinder 13 is a piston 16 provided with suitable sealing means 17 by which it is rendered leak-tight within said cylinder.

As shown in Figure 2, the upper portion of the central housing 7 is provided with right and left hand laterally extending integral housings or sleeve members 21, said members being provided with suitable bearing means in which a lifting rock shaft 23 is mounted for rocking movement. The central portion of the rock shaft 23 carries an arm 24 that is fixed thereto in any suitable manner, and arranged to extend in a generally downward direction within the central housing 7. The outer end of the arm 24 carries a pin 25, and a pair of pitman straps 26 serve to connect said pin with a wrist pin 27 carried by the piston 16 adjacent the forward end thereof. By this means, therefore, the piston 16 is operatively connected with the rock shaft 23 so that when the piston is forced outwardly of the cylinder 13, or to the left as viewed in Figure 1, the rock shaft 23 is rocked in a clockwise direction. The rock shaft 23 is provided with squared ends 29 to receive lifting arms (not shown) whereby said rock shaft may be connected

by any suitable lifting connections with implements or other operating units associated with the tractor.

The piston 16 is operated by pressure derived from a hydraulic pump of the positive displacement type. The pump is indicated in its entirety by the reference numeral 31, and as shown in Figures 1 and 2 it comprises a suitable housing 32 that is carried by and secured to the rear wall 33 of the central housing 7 by bolts 34. A pair of steel dowel pins 35 carried at opposite ends of the housing 32 and adapted to be inserted in openings provided therefor in the rear wall of the central housing 7 serve to align the holes for the bolts 34 in the housing 32 and the central housing 7 in the assembling operation. The pump gears are indicated by 37 and 38, the gear 37 being journaled on a bearing 39 supported on a short shaft 40 disposed in sockets 41 and 42 formed in the pump housing casting 32 and in the rear wall 33 of the power lift housing 7. The other pump gear 38 is provided with three keyways or slots 43 (Figures 1 and 2) in one of which a key 44 (Figure 2) is placed for securing the gear 38 to a power take-off shaft 46 which extends forwardly into the tractor body 1 and is operatively connected with the tractor motor by any suitable means. The purpose of providing the additional slots 43 will be explained later herein. The shaft 46 extends rearwardly longitudinally of the tractor between the two main driving gears 4 and through an opening 47 in the rear wall 33 of the power lift housing 7 (Figure 1) and is journaled in a bearing 48 supported by the pump housing 32. A cap 51 is provided for closing the opening that receives the bearing 48, and the rear end of the power take-off shaft 46 extends through said cap and is sealed by suitable bushing means 52. A sealing washer 50 is also provided between the cap 51 and the shaft 46 on the inner side of the bushing 52. The rear end of the shaft 46 is splined, as shown at 53, to receive suitable power take-off connections by which any operating unit or units may be driven by the rotation of said shaft.

The pump gears 37 and 38 are rotated in the direction of the arrows in Figure 2 by the rotation of the shaft 46, and such rotation of the gears builds up pressure in one side of the pump housing 32 and creates a suction in the other side of the housing. On the suction side of the pump housing the rear wall 33 of the power lift housing 7 is provided with an opening 55 (Figure 2), and a similar opening 56 is provided on the other side of the pump housing 32 at the pressure side of the pump 31. The opening 55 affords communication between the suction side of the pump and the lower portion of the housing 7, which forms a reservoir R for the hydraulic fluid, and the opening 56 leads into a vertically disposed pressure channel 57 formed in a thickened section 58 at the rear wall 33, as best shown in Figures 1 and 6. In Figure 2 the vertical pressure channel 57 is indicated in dotted lines, and the upper terminal end 59 thereof (Figure 6) communicates with an opening 61 in the valve housing 62 that contains the valve mechanism for controlling the power lift mechanism. The opening 61 communicates with an upwardly curving passageway or pressure chamber 63 (see Figures 3 and 9) formed in the valve housing 62 and which will be referred to later.

In the central portion of the housing 7 a section 64 extends from the rear wall 33 to the front wall 11 thereof and is provided with an interior chan-

nel or bore 65 leading from a registering opening 66 (Figures 1 and 6) formed in the valve housing 62, said registering opening being provided with a valve 67, the purpose of which will be described later.

The forward end of the channel 65 registers with a channel 68 formed in the lower section of the cylinder casting 13, and the channel 68 leads forwardly and into the closed end of the cylinder 13, as best shown in Figure 1.

The valve housing 62 encloses all of the valve parts and associated controlling mechanism, as best shown in Figures 1 and 2, and this valve mechanism is arranged to control the flow of fluid between the pressure conduit 57 and the channels 65 and 68 communicating with the closed end of the cylinder 13. As best shown in Figures 2 and 6, the valve housing 62 also includes a lower chamber 69 that is separated from the upper chamber 63 by a wall 70 (see Figures 2 and 4), and communicates through the opening 66 above described with the channel 65. The upper portion of the lower chamber 69 communicates with the upper chamber or curved passageway 63 through a valve opening 71 that is controlled by a valve 72. As above described, the liquid under pressure from the pump 31 is forced upwardly through the pressure channel 57 and through the opening 61 into the upper pressure chamber or curved passageway 63, and if the valve 72 is open, the liquid will pass through the opening 71 into the chamber 69 and around through the opening or port 66 into the bore 65, whence the liquid passes through the channel 68 into the closed end of the cylinder 13.

The upper pressure chamber 63 is extended upwardly to form a chamber section 73 (see Figures 3 to 5) and communicates through an opening 75 with the space 76 above the wall forming the upper portion of the pressure chamber 63, which space 76 has direct communication with the upper portion of the reservoir R as shown in Figure 2.

The valve 72 is fixedly mounted on a stem 81 which passes through a bushing 82 in the section forming the upper wall of the chamber 63, and at its upper end the valve stem carries a sleeve 83 which is of generally cylindrical formation and is slidable in a cylindrical opening 85 formed in the section 86 of the valve housing 62 that forms the upper wall of the upper chamber section 73. The sleeve 83 is of the same diameter as the diameter of the opening 75 above mentioned, so that said sleeve serves as a valve closure for such opening, as will appear later, and the stem 81 is of such a length as to permit the valve 72 to move well toward its full open position before the sleeve or plunger 83 approaches the opening 75.

The entire unit, comprising the valves 72 and 83, may be shifted to three different positions. Figure 3 shows the position in which the valve 72 is opened a small amount, but the valve 83 is caused to remain substantially in its wide open position. Since this latter valve is still in its wide open position, no pressure is developed by the pump since the liquid in the pressure chamber 63 merely discharges back into the reservoir R through the opening 75. However, since the valve 72 is now open, the liquid within the closed end of the cylinder 13 may escape by flowing backwardly or rearwardly through the channels 68 and 65 into the chamber 69 and up past the valve 72 and through the opening 71 into the chamber 63, whence it is discharged into the res-

ervoir R through the opening 75. Thus, the opening of the valve 72 relieves any pressure within the cylinder 13 occasioned by any reaction of the load acting against the piston through the rock shaft 23 and the arm 24. The above mentioned positions of the valves 72 and 83 are those to which they are moved when the rock shaft is to be rocked to lower the implements, as will hereinafter appear.

10 The second position of the valve unit is illustrated in Figure 4. In this position the valve 83 closes off the opening 75 entirely and opens the valve 72 to its wide open position. Now the liquid forced upwardly through the pressure channel 57 into the pressure chamber or curved passageway 63 passes downwardly through the opening 71 and into the chamber 69, from whence the liquid flows under pressure through the passageway 66 into the channels 65 and 68 and into the closed end of the cylinder 13. Since the valve 83 is closed, direct communication between the pump and the reservoir is cut off, and the pressure developed by the pump is all imposed on the piston 16, with the result that it moves from its position shown in Figure 1 and swings the arm 24 connected with the rock shaft in a clockwise direction to thereby rock the rock shaft to raise the implements connected with said rock shaft.

15 The third position of the valve unit is illustrated in Figure 5, and is the position to which said parts are moved when the raising of the implements has been accomplished, and in which position of the parts the fluid is trapped so as to hold the implements in such raised position. 20 When in this third position, the valve 72 is closed, which prevents the pressure in the pressure chamber or passageway 63, communicated thereto through the channel 57 from the pump 31, from entering into the chamber 69 and into the cylinder 13. In this position of the valve means, however, the cylindrical valve 83 is open, thus leaving the opening 75 unobstructed so that the liquid under pressure being delivered to the chamber 63 from the pump may pass therefrom through the upper chamber section 73 thereof and out through the opening 75 back into the reservoir R. It will be seen, therefore, that in this position of the valve unit the pump will 25 run free and no pressure will be transmitted to the cylinder 13. It will also be noted that any liquid that is trapped in the closed end of the cylinder 13 is held therein by the closing of the valve 72, since the opening 71 is the only means by which the liquid in the closed end of the cylinder 13 can escape. Thus, the piston 16 is held hydraulically locked in the position it occupies when the valve 72 is closed. Suitable means, which will be described later, has been provided 30 by which the movement of the piston 16 toward its left hand limit, as viewed in Figure 1, automatically shifts the valve means from the position shown in Figure 4 to the position shown in Figure 5.

35 The means for controlling the valve mechanism is indicated in its entirety by the reference numeral 91 and will now be described. This means includes a cam member 92 mounted in the upper portion of the valve housing 62 and adapted to 40 be progressively advanced from one position to another in succession for the purpose of, first, emptying the cylinder 13 to permit the load to lower by shifting the valve means to the position shown in Figure 3, then applying pressure to the piston 16 by shifting the valve means to the posi-

tion shown in Figure 4 to cause the pressure of the pump to force the piston outwardly, and then, lastly, shifting the valve means to the position shown in Figure 5 for hydraulically locking the piston in its outer position.

The valve unit comprising the valve members 72 and 83 is biased for movement toward the position shown in Figure 5 by a spring 94 which is disposed in the chamber 69. This spring 94 is seated in a plug 95 which is provided with a suitable recess for receiving the lower end of the valve spring 94 and is threaded into an opening in the lower portion of the valve housing 62 as best shown in Figures 2 to 5. The valve operating cam 92 bears upon the top of the cylindrical valve plunger 83 of the exhaust port 75, and said cam has a section of maximum throw, indicated by the reference numeral 96, that engages the valve member 83 when the power lift is raising, as shown in Figure 4. At the end of the raising stroke the cam is automatically turned through a comparatively small angle, as will be herein-after described, allowing the valve to be forced upwardly by the spring 94 against a cam section 97 of minimum throw, as shown in Figure 5. From this position the cam 92 is turned approximately 180° to the position shown in Figure 3, causing the power lift to lower. When in this latter position the valve 72 is opened, thereby permitting the oil from the cylinder to pass backwardly as above described and escape through the port 71. With the parts in this position the port 75 is also open so that the fluid from the pump entering the passageway or pressure chamber 63 will also escape through the port 75 into the reservoir R.

The cam member 92, together with several other cams to be mentioned later, is formed as an integral part of a casting 101, as best shown in Figure 11, said casting being journaled for rotation on a rock shaft 102 supported in bearings 103, 104 in the upper portion of the power lift housing 62 as shown in Figure 2. The rock shaft 102 is provided with a crank arm 105 at one end (Figure 2) which is connected by a link 106 to a trip lever or foot pedal 107 fixed to one end of a shaft 108 that is journaled in a pair of lugs 109 formed integral with or fixedly secured to the sleeve members 21 at the upper portion of the central housing section 1. Suitable packing means 98 held in position by a spring 99 (Figure 2) seals the rock shaft 102 in the valve housing 62. At the opposite end of the shaft 108 is fixed a second trip lever or foot pedal 107' whereby the link 106 may be actuated by operating either of said levers 107 or 107', as will be readily understood. A coiled torsion spring 110 supported on the shaft 108 between the lugs 109 has one end hooked over the foot pedal 107 and its opposite end in engagement with the left hand lug 109 as viewed in Figure 2, said spring acting to immediately return the foot pedals 107 and 107' to their normal positions and to swing the crank arm 105 downwardly to the position shown in Figure 2, after the operator's foot has been removed therefrom after depressing the same to actuate the cam mechanism, as will be readily understood.

By stepping on either of the foot pedals 107 or 107' the cam shaft 102 can be rocked alternately between two predetermined positions. This rocking movement is transmitted to drive the cam assembly 101 in a unidirectional rotation through a pawl 111 that is pivoted by a pin 112 (Figure 1) to an arm 113 that is carried on a hub

member 114 clamped to the cam shaft 102 as best shown in Figure 11. The pawl 111 is biased, as by a spring 115, for engagement with a ratchet wheel 116 (see Figure 1) that is formed integral with the cam assembly 101 (Figure 11). The foot pedal, linkage, and ratchet mechanism are so designed that for each operation of the pedal to its extreme down position the cam assembly will be rotated approximately 180°, but, as will hereinafter appear, it is not necessary that the foot pedal be depressed to its extreme down position as means have been provided to move the cam assembly after the foot pedal has been depressed to a predetermined point. It will be noted also, in this connection, that the ratchet wheel 116 is provided with four notches 117 spaced 90° apart as shown in Figure 1, and the purpose of providing the two additional notches will be explained later.

As best shown in Figure 11, the cam assembly 101 also includes a power cam 121 provided with two sections 122 and 123 of minimum radius spaced 180° apart, and also with two other sections 124 and 125 of maximum radius also spaced 180° apart. This power cam is engaged by a cam following roller 126 which is journaled on one end of an arm 127 fixedly connected at its opposite end to a hub 128 rotatably supported on a shaft 129 suitably journaled in bearing portions 131 formed integral with the housing 62 as shown in Figure 2. A second arm 132 formed integral with the hub member 128 extends upwardly from the latter and is provided at its outer end with a spring abutment 134. A coiled compression spring 135 having one end disposed over a lug 136 on the spring abutment 134 and its other end disposed over a lug 137 (Figure 3) on an integral portion 138 of the housing 62 reacts against the housing portion 138 and exerts a force against the abutment 134 to force the roller 126 against the cam 121. In the extreme raised and lowered positions of the power lift, the roller 126 is at rest in one of the low points 122, 123 on the cam 121 as shown in Figures 3 and 5. When, however, the cam assembly 101 is rotated by the foot pedal mechanism, the roller 126 is forced outwardly by the cam 121 against the compression of the spring 135 until such roller passes one of the high points 124, 125 of the cam. Thus in moving from the position shown in Figure 3, which is the position when the implements are lowered, to a position which will cause the power lift to raise the implements, as shown in Figure 4, the roller 126 passes from the low point 122 over the high point 124 of the cam, after which the compression of the spring 135, acting through the roller 126, is sufficient to rotate the cam 121 and the entire cam assembly formed integral therewith into the position shown in Figure 4, at which point the rotation of the cam assembly is interrupted by a third cam 141 that is formed integral with said cam assembly and is best illustrated in Figure 7.

The cam 141 is provided with an abutment 142 between the high and low points thereon which is adapted to abut against the outer end of a stop arm 143 fixed to or formed integral with a hub member 144 journaled on the shaft 129 that supports the hub member 128 before mentioned. This stop arm 143 is yieldingly urged into a position to abut the cam 141 by a compression spring 145 acting against a second arm 146 fixed to the hub member 144 and extending downwardly therefrom, said spring re-

acting against the rear wall of the housing 62, as shown in Figure 7. The positions of the several parts as shown in Figure 7 correspond to the positions of the parts shown in Figure 4 in which the valve mechanism is set for raising the power lift.

When the piston 16, which is connected to the actuating arm 24 on the power lift rock shaft 23 as above described, nears the end of its travel in the raising operation, that is toward the left as viewed in Figures 1 and 7, the lower end of the arm 24 engages a pin 148 that is slidable longitudinally in an opening 149 extending through a lug 151 fixed to or formed as an integral part of the housing 62. As the piston completes its stroke the pin 148 is moved against the lower end of the arm 146 and rotates said arm against the action of the spring 145 in a clockwise direction. As both the arm 146 and the stop arm 143 are fixed to the hub 144 this movement of the arm 146 moves the stop arm 143 also in a clockwise direction and out of engagement with the abutment 142 on the cam 121. It will be noted in this connection that in Figure 4 the roller 126 has not quite reached the low point 123 of the cam 121, and the reason for this is that the rotation of the cam assembly was interrupted by the stop arm 143 engaging the abutment 142 on the cam 121 as above described. However, when the stop arm 143 is disengaged from the abutment 142 when the piston 16 reaches the end of its stroke in the raising operation, the pressure of the roller 126 against the cam 121 will rotate the entire cam assembly from the position shown in Figure 4 to the position shown in Figure 5, where it is held by the roller 126 resting in the low point 123 of the cam 121. When the parts are in the position shown in Figure 5 the implements connected with the rock shaft 23 are in raised position as has been above described. The pin 148 also acts to prevent any accidental excessive amount of rearward movement of the piston 16, whereby the arm 24 might be jammed into the valve control mechanism, as the headed forward end 148' of the pin contacts the lug 151 in the rearward movement of the pin and absolutely limits the rearward movement of the piston, as will be readily understood.

Now, if it is desired to lower the implements, either trip lever 107 or 107' is again depressed to rotate the cam assembly to move the high point 125 of the cam 121 past the roller 126, and it can then be released immediately, as the cam assembly will continue to be rotated by the power of the spring 135 until the roller 126 comes to rest in the low point 122 of the cam 121, which brings the parts into the position shown in Figure 3 which is the lowered position of the implements.

It will be seen from the foregoing, therefore, that by providing the power cam 121 which is automatically moved by the cam roller 126 after the ratchet wheel 116 has been moved by actuation of the trip lever to rotate the entire cam assembly to move either high point 124 or 125 of the power cam past the cam roller, the cam roller 126 will act to automatically move the cam 121 until the cam roller comes to rest in either low point 122 or 123 of the power cam 121. Thus it will be seen that it is only necessary that the trip lever be depressed sufficiently to rotate the cam assembly through slightly more than 90°, after which the power cam 121 will act to move the entire cam assembly through the remainder of its movement. If, however, in actuating the

foot pedal in either the raising or the lowering operation the operator should release the pedal before it has been depressed far enough to move the high point 124 or 125 of the cam 121 past the roller 126, the pressure of the roller against the cam will force the cam assembly back into the normal position that it had previously occupied before the foot pedal was depressed, with the roller 126 at rest in one of the low points 122 or 123 of the cam, which would result in the implements remaining in a raised or lowered position, and it would be necessary for the operator to again depress the trip lever in order to raise or lower the implements.

As above mentioned, the ratchet wheel 116 has been provided with four notches 117 spaced 90° apart, although two oppositely disposed notches would be sufficient for an operative structure, and the purpose of providing the additional intermediate notches will now be pointed out. If, after the operator depresses the foot pedal to rotate the cam assembly, such assembly should stick before it has completed its cycle, as may occur if the oil is so stiff that the power cam 121 has insufficient capacity to rotate the cam through the remaining portion of its stroke, the operator will naturally again depress the foot pedal. Upon this second depression of the pedal the dog 111 will engage in the intermediate notch and assist the power cam in moving the cam assembly to its final position.

While it is believed that the operation of the valve mechanism and the means for actuating the same in the raising and lowering operations will be apparent from the foregoing description thereof, it is thought best to briefly describe the same. Assuming that the control mechanism has previously been operated to lower the implements, and the rock shaft and piston have been moved to the position shown in Figure 1, the valve mechanism will be in the position shown in Figure 3, and the cam roller 126 will be at rest in the low point 122 of the power cam 121. Now if the trip lever 107 is depressed, the arm 113 will be rocked and the ratchet dog 111 will shift the ratchet wheel 116 and the entire cam assembly formed integral with said wheel through approximately 180°. The curve of the valve cam 92 is such that the high point 96 thereof has moved the valve unit downwardly, against the tension of the spring 94, sufficiently to completely close the valve 83 and completely open the valve 72 as shown in Figure 4. No oil can now escape back to the reservoir and all of it is forced through the opening 71 and into the chamber 69 and the channels 65 and 68, toward the closed end of the cylinder 13. This forces the piston 16 toward the left in the cylinder 13, which, by reason of the connection of the pitman straps 26 with the lower end of the rock shaft actuating arm 24, causes the rock shaft 23 to be rocked and the implements or other load connected therewith to be lifted. In this operation the cam 141 is also rotated through approximately 180° into the position shown in Figure 7, in which position the spring controlled arm 143 comes into engagement with the abutment 142 on the cam 121, and momentarily arrests the movement of the cam assembly. As the piston 16 nears the end of its raising movement, the lower end of the rock shaft actuating arm 24 strikes the pin 148 which in turn moves the arm 146, against the action of the spring 145, toward the left as viewed in Figure 7, swinging the arm 143 formed integral with the arm 146 out of engagement with the

abutment 142 on the cam 141 and thereby unlocking the cam. Upon unlocking of the cam 141 the cam roller 126 under the action of the spring 135 will force the power cam 121 to rotate until the roller 126 comes to rest in the low point 123 of the power cam as shown in Figure 5. This movement of the power cam 121 rotates the valve cam 92 sufficiently to move its high point 96 off of the top of the valve 83 and bring the low point 97 of said cam 92 over the top of the valve 83, at which time the valve unit is moved upwardly under the action of the valve spring 94 to bring the top of the valve 83 into contact with the low point 97 of the cam 92 as shown in Figure 5. This movement of the valve unit opens the valve 83 and completely closes the valve 72. When the parts are in this last mentioned position the oil between the valve 72 and the piston is trapped and hydraulically locks the lift mechanism in a raised position, and the pump is caused to discharge directly into the reservoir R through the opening 75. To lower the implements the operator again depresses the trip lever sufficiently to rotate the cam assembly until the cam roller 126 rides over the high point 125 on the power cam 121, and the cam roller 126 under the action of the spring 135 then forces the power cam to move the entire cam assembly again into the position shown in Figure 3, which opens the valve 72 slightly and breaks the hydraulic lock, permitting the implements to move to lowered position. In this position of the parts the valve 83 is also open and the pump runs free.

As above mentioned, the hydraulic power lift mechanism of the present invention is adapted to be used in connection with farm tractors for raising and lowering implements or other parts that are carried by the tractor, and such implements, as is well known in the art comprise various kinds, some of which are light in weight while others are relatively heavy. While it is desirable that light implements, such as cultivators, be dropped quickly, it is very important that heavy implements, such as listers, planters, etc., be dropped more slowly on account of the danger of damage to the tools, and, therefore, in the present construction means have been provided whereby the speed of lowering of the implements connected with the rock shaft 23 may be regulated, and this is accomplished by adjusting the limit of closure of the valve 67 which registers with the port 66 between the chamber 69 and the bore or channel 65, which parts have been before referred to. As best shown in Figures 1 and 6, the valve 67 is forced toward a closed position by a compression spring 161 having one end seated in a recess 162 formed in the housing section 64 and its opposite end engaging the valve. On the side opposite the spring 161 the valve is provided with a relatively long valve stem 163 that extends through an opening provided therefor in the bottom wall 164 of the housing 62. The opening through which the valve stem 163 extends is enlarged and internally threaded adjacent its outer end as shown at 165 to receive a set screw 166 that engages the outer end of the valve stem. The set screw is adapted to be locked in any adjusted position by a lock nut 167, and a protecting cap 168 is provided for the outer end of the set screw 166. By this construction, when the oil is being forced under pressure through the opening 66 and into the cylinder as above described to actuate the power lift to raise the implements, the oil forces the valve 67, against the compression of the spring 161, to its extreme open position in con-

tact with the edge 169 of the spring recess, allowing free passage of the oil irrespective of the setting of the screw 166. During the return movement of the piston 16, however, the oil flows back to the valve 67 as has been before described, and the combined pressure of the oil and the spring 161 acting against the valve 67, returns it to its closed position, as limited by the set screw 166. It will thus be apparent that by adjusting the valve by means of the set screw 166, the rate of return flow of the oil from the piston 16 can be adjusted over a wide range, thus adjusting the rate of speed of the return of the piston to the position it occupies when the implements are in lowered position.

In the present construction means have been provided for insuring the return of the power lift rock shaft 23 to lowered position regardless of whether or not there is an implement attached to the rock shaft, and this means is shown in Figure 8 and will now be described. This means comprises a helical spring 181 that is disposed around the rock shaft 23 within one of the laterally extending sleeve members 21 of the power lift housing 1. One end of this spring is attached to a pin 182 fixed on the rock shaft 23 while the opposite end of the spring is anchored in a bushing 183 which is screw threaded into the outer end of the sleeve member 21 and is rigidly held in position by bolts 184. This bushing 183 also acts as an outer bearing for the rock shaft 23 within the sleeve member 21. By this construction, when the hydraulic mechanism is actuated to rock the rock shaft to a position corresponding to the raised position of the implements the spring is stressed by such rocking movement, and when the hydraulic mechanism is actuated to return the parts to a position corresponding to the lowered position of the implements the spring 181 will operate to return the rock shaft to such position.

Suitable overload release mechanism has been provided, and in the present construction such mechanism is readily accessible from outside of the power lift housing, so that it is not necessary to remove the casing to obtain access to the valve. The location of this safety valve is best shown in Figures 1 and 9 and is positioned near the rear of the control housing 62. This valve is indicated by the reference numeral 191 and normally closes a passage 192 between the chamber 63 and the top portion of the reservoir R. The valve 191 is held closed by a heavy coiled spring 193 that bears at one end against the valve 191 and at its other end against a stud bolt 194. By this construction, whenever the pressure in the pressure channel 57 and in the chamber 63 exceeds a certain maximum, the valve 191 will be forced open against the action of the spring 193 and permits the oil in the chamber 63 to escape through the passage 192 into the reservoir R. Access may readily be had to the safety valve 191 by merely removing the stud bolt 194 and withdrawing the spring 193 through the bolt hole.

65 A sump 201 is provided at the bottom of the reservoir R as shown in dotted lines in Figure 2 and in plan section in Figure 10. This sump 201 is disposed at one side of a compartment 202 that is provided in the power lift housing to receive the power take-off shaft 46 before described. 70 The bottom of the sump 201 is provided with a drain 203 that is closed by a plug 204. By this construction, by removing the plug 204 and allowing a portion of the fluid to flow from the reservoir, any particles of grit or metal collected

in the sump can be drained off without the necessity of draining off all of the oil from the reservoir.

As above mentioned, the rear end of the power take-off shaft 46 is supported in a bearing 48, and in the present construction this bearing is lubricated by oil leaking along the sides of the gears 37 and 38 from the high pressure side of the pump, and in order to prevent the oil pressure in the bearing housing from building up to a point where leakage through the rear seal 50, 52 would take place, the extra keyways or slots 43 before mentioned have been provided in the gear 38 of the pump that is fixed to the power take-off shaft in order to conduct the oil from the bearing housing through the gear and into the compartment 202 (Figure 1) from which it flows through an opening 201 (Figure 10) into the sump 201. At the forward end of the compartment 202 as viewed in Figure 1, we provide a second bearing support for the power take-off shaft 46 which is in the form of a sleeve 208, and this bearing sleeve is lubricated by oil from the axle housing 2 of the tractor, the oil flowing through a small opening 211 at the rear end of the bearing sleeve 208 and working through the bearing in a groove 212 provided in the power take-off shaft 46 as best shown in Figure 10. A sealing washer 213 held in place by a helical spring 214 surrounding the shaft 46 prevents the escape of the oil from the power lift pump into the axle housing 2.

Oil is inserted into the hydraulic unit through an opening 221 in the top of the casing 62 as shown in Figure 2, said opening being normally closed by a plug 222 threaded into the opening. This plug 222 is provided with a small boring (not shown) extending therethrough to provide a breather for the hydraulic unit. The unit is filled with oil up to the level of a plug 223 (Figure 2) threaded into an opening on the right side of the valve housing 62.

While we have shown and described above the preferred structure in which the principles of the present invention have been embodied, it is to be understood that our invention is not to be limited to the specific details shown and described above, but that, in fact, widely different means may be employed in the practice of the broader aspects of our invention.

We claim:

1. Control means for hydraulic mechanism having interconnected valve means for controlling the flow of fluid through said mechanism, comprising, in combination, a cam adapted to be advanced to move said valve means into successive positions, a trip lever, means for advancing said cam by actuation of said trip lever to move said valve means to one position, disengageable means for locking said cam after it has advanced to move said valve means into said one position, and means for automatically advancing said cam after it is unlocked for moving said valve means into a second position.

2. Control means for hydraulic mechanism having interconnected valve means for controlling the flow of fluid through said mechanism, comprising a cam adapted to be advanced to move said valve means into successive positions, a trip lever, means for advancing said cam by actuation of said trip lever, means for automatically advancing said cam after said trip lever has advanced said cam beyond a predetermined point, to move said valve means to one position, means for locking said cam after it has advanced to move said valve means into said one position, and

means for unlocking said cam, said automatic advancing means operating to advance said cam after it is unlocked for moving said valve means into a second position.

5. Control means for hydraulic mechanism having valve means for controlling the flow of fluid through said mechanism, comprising a rock shaft, a unidirectionally rotatable cam journaled on said rock shaft and adapted to be advanced to move said valve means successively between open and closed positions, means on said rock shaft for advancing said cam upon rocking of said shaft, a trip lever for rocking said rock shaft, a power cam fixed to said first cam and disposed coaxial with said rock shaft, and means for advancing said power cam to move said first cam after said trip lever has advanced said first cam beyond a predetermined point to move said valve means to one position comprising an arm pivotally mounted adjacent said rock shaft and swingable into engagement with said power cam, and a spring biasing said arm into engagement therewith.

4. Control means for hydraulic mechanism having valve means for controlling the flow of fluid through said mechanism, comprising a rock shaft, a cam journaled on said rock shaft and adapted to be unidirectionally advanced to move said valve means successively between open and closed positions, a ratchet wheel fixed to said cam, a trip lever for rocking said rock shaft, a pawl carried by said rock shaft and engaging said ratchet wheel whereby said cam is advanced by actuation of said trip lever, a power cam disposed coaxial with said rock shaft and fixed to said first cam, an arm pivotally mounted adjacent said rock shaft, a spring applying force to said power cam through said arm for advancing the latter to move said first cam after said trip lever has advanced said first cam beyond a predetermined point to move said valve means to one position.

5. For use in hydraulic mechanism having valve means controlling the flow of fluid through said mechanism, the combination of a cam member operable to successively move said valve means to different positions, means for advancing said cam member to one position, a second cam member integral with said first cam member, means engageable with said second cam member for locking said cam members in said one position, means for unlocking said cam members, and automatically acting means for advancing said cam members after unlocking thereof for moving said valve means to a second position.

6. For use in hydraulic mechanism having valve means controlling the flow of fluid through said mechanism, the combination of a cam member operable to successively move said valve means to different positions, means for advancing said cam member to one position, a second cam member integral with said first cam member, means engageable with said second cam member for locking said cam members in said one position, means for unlocking said cam members, and automatically acting means comprising a third cam member integral with said first two cam members and means for applying force to said third cam member to move the latter for advancing said cam members after unlocking thereof.

7. Control means for hydraulic mechanism having valve means for controlling the flow of fluid through said mechanism, comprising in combination, a cam adapted to be advanced from one position to a second position to adjust said

valve means, a trip lever, ratchet mechanism operable by said trip lever for advancing said cam from one operating position to a second operating position, a second cam fixed to said first cam, means for applying force to said second cam to move the latter either to advance said first cam if said ratchet mechanism has advanced said cams beyond a predetermined point, or to return said first cam to said one position if said ratchet mechanism is released before said cams have reached 10 said predetermined point, and means for arresting the movement of said first cam before it has reached said second operating position, said force applied to said second cam being effective to complete the movement of said cams after said 15 arresting means has been disabled.

8. Control means for hydraulic mechanism having valve means for controlling the flow of fluid through said mechanism, comprising in combination, an element adapted to be moved to shift said valve means, a manually actuated control member engageable with said element when moved in one direction to move the element, means separate from said control member for moving said element toward a working position 20 after said control member has moved the element beyond a predetermined point, releasable detent means for arresting the movement of said element before it reaches said working position, and

means for releasing said detent means, said element being moved to said working position by said separate means after said detent means has been released.

5 9. Control means for hydraulic mechanism having valve means for controlling the flow of fluid through said mechanism, comprising a rock shaft, a cam journaled on said rock shaft and adapted to be advanced to move said valve means, a ratchet wheel fixed to said cam, a trip lever for rocking said rock shaft, a pawl carried by said rock shaft and engaging said ratchet wheel whereby said cam is advanced by actuation of said trip lever, a power cam fixed to said first cam, a spring pressed roller applying force to said power cam for advancing the latter to move said first cam after said trip lever has advanced said first cam beyond a predetermined point to move said valve means toward a working position, releasable detent means for arresting the movement of said cam at a predetermined point before it reaches said working position, and means for releasing said detent means, said cam being moved to said working position by said spring pressed roller after said detent means has been released.
